UNITED STATES PATENT OFFICE.

HARRY F. ROACH, OF ST. LOUIS, MISSOURI.

RIGID-POINT FROG.

1,129,905.

Specification of Letters Patent. Patented Mar. 2, 1915.

Application filed February 16, 1912. Serial No. 678,094.

To all whom it may concern:

Be it known that I, HARRY F. ROACH, a citizen of the United States, residing at St. Louis, Missouri, have invented a certain 5 new and useful Improvement in Rigid-Point Frogs, of which the following is a full, clear, and exact description, such as will enable others skilled in the art to which is appertains to make and use the 10 same.

This invention relates to railway track structures, and particularly to cast metal frogs of the type in which the point is fixed or immovable. The cast metal frogs that 15 have heretofore been in use have not proved entirely satisfactory owing to the fact that a wheel in passing over the frog caused reverse strains which often resulted in breaking the casting. This was due to the fact 20 that the frog consisted of a one-piece rigid casting or integral mass of metal of such design that when a load was applied to one end of same the casting would fulcrum on the track ties in advance of the point where 25 the load was applied and thus cause the metal in the top of the casting to be stretched or placed under tension, and when the load passed over the fulcrum the metal in the top of the casting would be placed 30 under compression and the metal in the bottom of the casting would be stretched or placed under tension. In other words, when a wheel passed over a cast metal frog of the type heretofore in use the fiber of the metal 35 in certain portions of the casting would be alternately stretched and compressed and thus in time become ruptured.

The main object of my invention is to provide a cast metal frog of the rigid or 40 immovable point type which is so designed that reverse strains are materially reduced or practically eliminated, thus producing a serviceable cast metal railway track structure that will successfully carry ordinary 45 or excessive loads without breaking.

Another object is to provide a frog which is so designed that a guttered or double-flanged wheel will pass over same smoothly and without causing the outer flange of 50 the wheel to strike the wing rail a hard blow or shock when the wheel travels up over the wing rail in passing from the wing rail onto the point of the frog. And still another object is to provide a cast metal

frog which is so designed that the wing 55 rails will not break and spread laterally at the mouth of the frog when the inside wheel of a car truck is pushed laterally into engagement with the opposite wing rail to that on which the wheel is traveling by the 60 side thrust which the guard rail exerts on the outside wheel of the truck.

Other objects and desirable features of my invention will be hereinafter pointed out.

Figure 1 of the drawings is a top plan view of a frog constructed in accordance with my invention; Fig. 2 is a side elevational view of said frog; Fig. 3 is a vertical longitudinal sectional view taken on the line 70 3-3 of Fig. 1; Figs. 4, 5, 6, 7, 8, 9, 10, 11, 12, 13 and 14 are transverse sectional views of Fig. 1, taken on section lines whose numbers correspond, respectively, to the numerals of said figures; Fig. 15 is a top plan 75 view illustrating a modification of my invention; Fig. 16 is a side elevational view partly broken away of the frog shown in Fig. 15; and Fig. 17 is an enlarged detail view of a portion of the frog shown in 80 Figs. 15 and 16.

Briefly stated, my invention consists in a cast metal frog of the rigid or "immovable point" type that is composed of a plurality of sections which are combined in 85 such a manner that the load which one section is carrying will not be transmitted to the section in front of same, thus practically preventing reverse strains from being created by a wheel in passing over the frog. 90

In the preferred form of my invention as shown in Figs. 1 to 14, inclusive, the complete frog is formed from a single casting that is divided into several sections by means of vertical joints, spaces or slots 95 which extend transversely across the entire width of the casting but only partway through the casting in a vertical direction. By forming the casting in this manner I obtain a frog the running surface of which 100 is divided into several independent sections, each of which is capable of deflecting or moving slightly in a vertical direction without causing the metal in the casting to be alternately stretched and compressed to 105 such an extent that it will eventually rupture. I prefer to divide the casting into three sections, A, B and C, by means of two

- slots, joints or spaces 1 that extend transversely across the entire width of the casting at certain predetermined points between the ends of the frog, preferably between the 5 point and the heel of the frog and between the point and the mouth, said spaces 1 extending only partway through the casting in a vertical direction so as to leave integral portions or transversely arranged webs 1^a 10 of metal which tie the different sections of the casting to base plates. The intermediate section B is provided with an integral frog-point 2 and wing rails 3, the end section C to the right is provided with rail sections 3^a 15 that form continuations of the wing rails 3, and the end section A to the left is provided with rail sections 2^a that converge toward the frog-point 2 and thus form continuations of same.
- 20 The entire structure consisting of the intermediate section and the two end sections is supported principally by two base plates 4 arranged adjacent the joints between the different sections and formed integral with the transverse webs 1^a or blocks of metal that tie the sections to the base plates and hold said sections in alinement. The base plates 4 are secured in any suitable manner to track ties *w*, and open spaces 5 are formed 25 between the base plates 4 and the sections A, B and C of the casting, as shown in Figs. 2 and 3, so that only the extreme ends of said sections will bear upon the base plates. In other words, I provide webs of metal 1^a 30 for tying the sections A, B and C to base plates which are spaced far enough away from the under side of the different sections to permit said sections to deflect slightly in a vertical direction without striking against the base plates, thus producing a frog which 35 comprises two main supports, an intermediate section whose ends rest upon said supports, and end sections whose inner ends also rest upon said supports but are separated from the intermediate section of the casting by means of slots or spaces that extend transversely across the entire width of the casting.
- 40 In order to provide a substantial supporting surface for the frog throughout its entire length and thus relieve the track ties *w* from the entire load imposed upon the frog, I arrange ties *y* under the intermediate section B and under the end sections A and C of the frog, the top faces of the auxiliary supporting ties *y* being arranged in a higher horizontal plane than the top faces of the ties *w* on which the base plates 4 rest. If desired, the raised portions of the casting 45 which form the frog-point, wing rails, etc., can be made hollow and provided with suitable transverse strengthening webs, as shown in broken lines in Fig. 1 and the various transverse sectional views, and the 50 base plates 4 and also the base portions of

the end sections A and C can be cut out, as shown in Fig. 1, or designed in such a manner that all superfluous metal in these portions of the structure is eliminated.

55 In a frog of the construction above-described a vertical load applied to one of the end sections of the frog will be transmitted directly to the base plate on which said end section rests, and after the load has passed from the end section onto the intermediate section the load which said intermediate section carries will be transmitted to both base plates and not to the end sections of the frog. In view of the fact that said sections are supported at their extreme ends by base plates which are spaced away from the under sides of the sections sufficiently to permit said sections to deflect slightly in a vertical direction, there is very little tendency for the various sections to fulcrum on the ties. Consequently, there is no tendency for a cast metal frog of the construction above-described to break for practically no reverse strains are 60 created in the casting.

65 In order to reduce the liability of the casting breaking adjacent the mouth of the frog when a wing rail is subjected to an excessive lateral strain or shock from the inside wheel of a car truck, as usually occurs when the outside wheel of the truck comes into contact with the guard rail, I tie the base flanges of the wing rail extensions 3^a of the end section C together by means of a transversely disposed web 6 that is 70 formed integral with said base flanges, as shown clearly in Figs. 1 to 14, and if desired, the base flanges of the rail sections 2^a 75 on the opposite end section A of the casting can be tied together in a similar manner by 80 means of an integral web 7, as shown in Fig. 1.

85 In addition to the desirable features above-mentioned my frog comprises means for causing a guttered or double-flanged 90 wheel to travel over the frog smoothly and without subjecting the wing rails to a sharp impact or blow when the outer flange of the wheel rides up onto the tread of the wing rail in passing from the wing rail onto the 95 point. While I have shown this latter feature applied to a cast metal frog I do not 100 wish it to be understood that it is limited to a frog of this specific type for it is applicable to any rigid point frog irrespective 105 of whether the frog is cast in one piece or built up from short sections of T-rails.

110 The means which I employ for accomplishing this consists of flanges or risers 8 that project laterally from the wing rails 115 3 adjacent the throat of the frog whose top faces incline upwardly and merge into the tread surfaces of the wing rails at a point between the throat and the mouth of the frog, as shown in Fig. 1, said risers com- 120 125 130 135 140 145 150 155 160 165 170 175 180

5 mencing at a point adjacent the mouth of the frog in a lower horizontal plane than the tread surfaces of the wing rails and rising gradually to a point between the throat and the mouth where the top faces of said 70 risers merge into the tread surfaces of the wing rail, as shown in Fig. 2. When a guttered or double-flanged wheel passes through the frog the outer flange of the wheel comes 10 gradually into contact with the inclined riser 8 of the wing rail on which the wheel is traveling, thus causing the wheel to be lifted slightly and consequently does not cause the outer flange of the wheel to strike 15 the wing rail a sharp blow when it travels up over the wing rail in passing from the wing rail onto the point of the frog. In other words, the inclined risers 8 act as 20 wheel-tread surfaces for the outer flange of a guttered wheel and thus guide such a wheel smoothly onto the tread surface of the wing rail on which the wheel is traveling. Furthermore, said risers eliminate the 25 possibility of the outer flange of a double-flanged wheel hugging the side of the wing rail after the wheel has passed the throat of the frog, thus preventing the inner flange or main flange of the wheel from being drawn into engagement with the point of 30 the frog by reason of the outer flange hugging the side of the wing rail after the wheel has passed through the throat.

In Figs. 15 to 17, inclusive, I have illustrated a slightly modified form of my invention in which the intermediate section B' of the frog has no direct connection with the end sections A' and C' or with the main base plate 4^a of the frog, said intermediate section B' merely consisting of a separate casting or block of metal that bears at its opposite ends upon the base plate 4^a of the frog. As shown in Fig. 15, the base plate 4^a extends practically the entire length of the frog and is formed integral with the rail sections 12^a and 13^a that constitute the end sections A' and C', respectively, of the frog. The intermediate section B' is provided with an integral frog-point, wing rails and risers similar to those illustrated in Fig. 1, and joints or open spaces 11 are formed between the ends of said intermediate section B' and the end sections A' and C'. The base plate 4^a is provided with bearings 4^b on which the opposite ends of the intermediate section B' rest, and at approximately the center of said intermediate section B' is a bearing 9 that is normally spaced slightly away from a co-operating bearing surface 9^a on the base plate. The intermediate section B' rests 50 freely on the base plate and is prevented from moving longitudinally or transversely of the base plate by means of lugs 15 on the base plate that fit in notches in the intermediate section B', as shown in Fig. 15. I 55 also prefer to provide the base plate with

reinforcing and strengthening ribs 16 at the points of intersection between the intermediate section and the end sections, said ribs being on the under side of the base plate, as shown in Figs. 16 and 17.

70

A frog of the construction just described embodies practically the same desirable features as the frog shown in Fig. 1 owing to the fact that the intermediate section is supported in such a manner that there is no 75 liability of its fulcruming intermediate its ends when a wheel passes over same, and the end sections are separate and distinct from the intermediate section and consequently can move or deflect slightly in a vertical 80 direction relatively to said intermediate section.

80

If desired, inserts 17 can be arranged in the slots or open spaces 1 and 11 in the two forms of my invention illustrated in Figs. 1 and 15, respectively, but these inserts are not at all essential and can either be used or dispensed with as the manufacturer desires. In manufacturing a frog of the type shown in Fig. 1 inserts could probably be arranged 90 in the mold so as to form the joints or open spaces 1 between the sections but it would be immaterial whether or not these inserts were removed after the frog was installed for they would not interfere with the operation 95 of the frog or prevent one section from deflecting slightly relatively to the other.

90

Having thus described my invention, what I claim as new and desire to secure by Letters Patent is:

100

1. A cast metal frog of the immovable point type comprising several sections or portions which are separated from each other by transversely extending spaces that give a certain degree of flexibility to the 105 frog.

105

2. A frog of the rigid point type comprising a plurality of sections whose top portions or running surfaces are divided or separated by transversely extending slots.

110

3. A frog of the rigid point type comprising a plurality of sections whose top portions or running surfaces are divided or separated by transversely extending joints, and base supports arranged adjacent the 115 joints between said sections.

115

4. A frog of the rigid point type comprising a plurality of sections whose top portions or running surfaces are divided or separated by transversely extending slots, 120 and supporting base plates integrally connected to the ends of said sections.

120

5. A cast metal frog of the immovable point type whose running surface consists of a plurality of transversely divided sections, 125 and means for supporting the ends of said sections.

125

6. A rigid point frog consisting of a casting whose top surface is separated or divided into several sections by means of 130

transversely extending slots which extend partway through the casting in a vertical direction.

7. A rigid point frog consisting of a casting whose top surface is divided into a plurality of sections by means of transversely extending joints, and base plates spaced away from the under side of the end portions of said sections and connected to said sections by webs.

8. A railway frog consisting of two base plates which are adapted to be connected to track ties, and an intermediate section and two end sections resting at their ends upon said base plates and provided with top faces which form the running surface of a rigid point frog.

9. A railway frog of the rigid point type consisting of a casting provided with two base plates that are spaced away slightly from the under side of the casting and arranged adjacent the heel and mouth of the frog, the top surface of said casting being divided into a plurality of sections by means of joints that extend transversely across the casting.

10. A railway frog of the rigid point type consisting of a casting provided with two base plates that are spaced away slightly from the under side of the casting and arranged adjacent the heel and mouth of the frog, the top surface of said casting being divided into a plurality of sections by means of spaces that extend transversely across the casting.

11. A railway frog consisting of a cast metal structure that comprises a frog point, wing rails, and risers arranged outside of the wing rails adjacent the throat of the frog for guiding the outer flange of a guttered wheel up onto the tread surface of the wing rail as the wheel passes from the wing rail onto the frog point.

12. A railway frog consisting of a cast metal structure that comprises a frog point, wing rails, and risers integrally connected together, said risers being arranged outside

of the wing rails adjacent the throat of the frog and provided with upwardly inclined tread surfaces whose upper ends merge into the tread surfaces of the wing rails.

13. A railway frog comprising an intermediate section that is provided with a frog point, wing rails, and risers arranged outside of the wing rails adjacent the throat of the frog, end sections provided with rails that form continuations of said frog point and wing rails, and base plates on which the ends of said intermediate and end sections bear and to which they are integrally connected.

14. A cast metal railway frog provided at one end with rail sections which form continuations of the wing rails of the frog, and a transversely extending tie brace integrally connected to the base flanges of said rail sections.

15. A railway frog consisting of a continuous base plate provided at one end with rail sections that form continuations of the frog point and at its opposite end with rail sections that form continuations of the wing rails, and an intermediate section supported at its ends upon said base plate and provided with a frog point and wing rails.

16. A railway frog consisting of a continuous base plate provided at one end with rail sections that form continuations of the frog point and at its opposite end with rail sections that form continuations of the wing rails, an intermediate section supported at its ends upon said base plate and provided with a frog point and wing rails, and means for preventing said intermediate section from moving transversely or longitudinally of the base plate.

In testimony whereof I hereunto affix my signature in the presence of two witnesses, this twelfth day of February, 1912.

HARRY F. ROACH.
